UNITED STATES PATENT OFFICE.

SOCRATES A. XIPPAS, OF PITTSBURGH, PENNSYLVANIA.

DESIGN FOR AN ELECTRIC-FAN CASING.

Application filed April 16, 1926. Serial No. 17,314. Term of patent 3½ years.

To all whom it may concern:

Be it known that I, SOCRATES A. XIPPAS, a citizen of the United States, residing at Pittsburgh, in the county of Allegheny and State of Pennsylvania, have invented a new, original, and ornamental Design for an Electric-Fan Casing, of which the following is a specification, reference being had to the

accompanying drawing, forming part thereof.

The figure is a side elevation of an electric fan casing, showing my new design.

I claim:

The ornamental design for an electric fan casing, as shown.

SOCRATES A. XIPPAS.
